DESIGN FOR A BROILER OR SIMILAR ARTICLE

Sol Forman, New York, N. Y.

Application October 28, 1939, Serial No. 87,909

Term of patent 3½ years

To all whom it may concern:

Be it known that Sol Forman, a citizen of the United States and resident of New York city, in the county of New York and State of New York, has invented a new, original, and ornamental Design for a Broiler or Similar Article, of which the following is a specification, reference being had to the accompanying drawing, forming part thereof, and in which:

Fig. 1 is a side elevational view of a broiler, embodying my new design;

Fig. 2 is an elevational view showing the broiler hood mounted on the tray; and

Fig. 3 is an enlarged perspective view of the broiler, showing the tray, grill and hood separated from one another.

I claim:

The ornamental design for a broiler or similar article, substantially as shown.

SOL FORMAN.
